UNITED STATES PATENT OFFICE.

JAMES J. BREACH, OF BOSTON, MASSACHUSETTS.

MACHINE FOR CUTTING ARTICLES FROM SHEET MATERIAL.

SPECIFICATION forming part of Letters Patent No. 678,935, dated July 23, 1901.

Application filed July 14, 1900. Serial No. 23,600. (No model.)

To all whom it may concern:

Be it known that I, JAMES J. BREACH, a citizen of the United States, residing at Boston, in the county of Suffolk and State of Massachusetts, have invented certain new and useful Improvements in Machines for Cutting Articles from Sheet Material; and I do hereby declare the following to be a full, clear, and exact description of the invention, such as will enable others skilled in the art to which it appertains to make and use the same.

The present invention relates to machines for cutting articles from sheet material, and more particularly to machines for cutting boot or shoe soles from leather, leather-board, or other suitable material.

One object of my invention is to provide a machine whereby a sheet of material may be cut into articles of curvilinear or other desired outline with a minimum amount of waste and whereby each article may be cut from any desired portion of the sheet.

In my Patent No. 589,409, dated September 7, 1897, I have disclosed a machine for cutting out boot or shoe soles, comprising a work-support and a traveling reciprocating knife coacting therewith, the knife and its guiding mechanism being mounted so as to be capable of a rotary movement about the center of the path traveled by the knife. The support for the knife and its guiding mechanism is not, however, bodily movable over the work-support, and in using the machine for cutting out shoe-soles from a large sheet of sole-leather the sheet must be moved on the work-support by the operator to the proper position after each cutting operation. This manipulation of the work is difficult, especially for large sheets, as the sheet must be turned and moved in various directions to avoid the damaged portions and to cause the soles to be cut out with a minimum amount of waste.

Another of the objects of my present invention is to do away with the necessity of thus moving the work relatively to its support, and in accomplishing this object I so mount the cutting mechanism and the work-support as to be relatively movable, whereby the work can be properly positioned beneath the cutting mechanism without being moved on its sup-

port. By so mounting the cutting mechanism and work-support I am enabled to provide a machine in which a large sheet of material can be rapidly cut into articles of predetermined shape, the cuts in the sheet being arranged in any desired manner to secure a uniform stock in the articles and a utilization of the greatest possible amount of the sheet.

I am aware that machines for cutting articles from sheet material have heretofore been devised in which the work-support is fed forward uniform distances between the cutting operations to present an uncut portion of the sheet to the cutting mechanism. In such machines, however, the movement of the support has been controlled entirely by the feeding mechanism and the support has not been so mounted as to be freely movable to present any desired portion of the sheet to the cutting mechanism. In machines provided with a positive feed mechanism the cuts in the sheet will be arranged in a certain definite order regardless of defects or variations in the material of the sheet. In a machine embodying my invention, however, the cutting mechanism and the work-support are so mounted as to be freely movable relatively to each other, whereby any desired portion of the sheet may be presented to the cutting mechanism and articles of uniform stock free from defects produced.

In the preferred form of my invention I arrange the cutting mechanism so as to be movable with relation to the work-support, the construction for permitting this movement consisting of a carriage movable over the work-support and an arm or frame movable with relation to the carriage and supporting the cutting mechanism.

The form of cutting mechanism which I consider the best comprises a reciprocating knife arranged to travel in a path corresponding to the shape of the article to be cut out; but I do not consider my invention in its broadest aspects as limited to such specific cutting mechanism.

In addition to the means above referred to for giving the cutting mechanism movement with relation to the work-support I also desirably so mount the cutting mechanism that it can be given another movement to change

the direction of the cut on the sheet, as by mounting it so as to be rotatable on the arm above referred to.

As a work-support I provide a platen of appropriate size provided with a surface to coact with the knife of the cutting mechanism. Where a large platen is used, as in my present invention, and where the cutting mechanism acts upon different portions of the platen in cutting the articles from the sheet, the surface will remain true for a much longer period than in those machines in which the cutting mechanism always acts upon the same portion of the platen. The surface of the platen must, however, be trued up occasionally, and in order to perform this operation satisfactorily and to avoid the necessity of removing the platen from the machine I provide a cutting attachment, whereby the surface of the platen may be trimmed while in position in the machine as often as may be desired.

With the above objects in view my invention consists in the devices and combinations of devices hereinafter described and claimed.

In the machine hereinafter specifically described as embodying my invention the cutting mechanism is of the same general type as that disclosed in my Patent No. 589,409 and in my application for patent, Serial No. 23,599, of even date herewith, in which one or more reciprocating cutting-knives are caused to travel about the periphery of a pattern-plate of a shape corresponding to that of the sole to be cut out.

In the accompanying drawings, which illustrate a machine embodying a preferred form of my invention, Figure 1 is a view in side elevation of a complete machine embodying the same. Fig. 2 is a view taken on the line 2 2, Fig. 1, showing the cutting mechanism in side elevation and the carriage from which it is supported in end elevation, the attachment for trimming the surface of the platen having been removed. Fig. 3 is a sectional view on the line 3 3, Fig. 4. Fig. 4 is a sectional view on the line 4 4, Fig. 2. Fig. 5 is a sectional plan view on the line 5 6, Fig. 2, looking up, and Fig. 6 is a sectional plan view on the same line looking down. Fig. 7 is a sectional plan view on the line 7 7, Fig. 2. Fig. 8 is a detail sectional view on the line 8 8, Fig. 6, showing, on an enlarged scale, the construction and actuating mechanism of one of the cutting devices. Fig. 9 is a detail sectional view on the line 9 9, Fig. 8, drawn to a still larger scale. Fig. 10 is a detail perspective view of the mechanism for locking the knife-carrier in retracted position. Fig. 11 is a view in side elevation of a modified form of knife-carrier. Fig. 12 is a sectional view on the line 12 12 of Fig. 11. Fig. 13 is a view in side elevation of the devices shown in the lower part of Fig. 11 looking in the opposite direction; and Fig. 14 is a front view, partly in section, of the devices shown in Fig. 13.

Referring to the drawings, the frame of the machine consists of the base 1, the standards 2 2, projecting outwardly and upwardly therefrom, and the cross-piece 3, connecting the upper ends of the standards. The cross-piece 3 is formed as a hollow open-bottomed casing, and the lower edges of its downwardly-extending sides are provided with inwardly-projecting flanges 4, which form supporting-guideways for a reciprocating carriage, from which the cutting mechanism is supported.

5 designates the base-plate of the carriage, and 6 four lugs secured to or formed on the upper surface thereof. In vertical slots in the lugs 6 are secured, by means of the nuts 7, short studs or shafts 8, upon which are mounted rollers 9, adapted to engage the upper surface of the flanges 4. The lugs 6 are set back from the edge of the plate, which extends outwardly beneath the flange 4. The carriage is thus securely held and guided by the engagement of the flanges by the rollers 9 and edges of the plate 5, lateral movement 90 of the carriage being prevented by the lugs 6 and inner edges of the flanges 4.

A block 10 is secured in an opening in the plate 5 near one end, the block being provided with a shoulder bearing against the under surface of the plate and being secured thereto by screws 11, passing upwardly through the block into the plate. The portion of the block extending below the plate 5 forms a pivot for an arm or frame 12. A flange or shoulder is formed at the lower end of the block 10, and the opening in the arm 12 is shaped to fit the block and flange, so that the arm is supported by the block. The opposite end of the arm 12 is supported by a segmental guide-rail 13, secured, as by screws 14, to the under side of the plate 5. This guide-rail has a recess cut in its top and side next to the arm 12, as shown in Fig. 4, and in this recess a strip of metal 15 is placed, provided with a raceway for containing a series of balls 16, upon which the end of the arm 12 rests.

The parts by which the cutting mechanism is directly supported are revolvably mounted in the arm 12, as follows: The free end of the arm 12 is formed with a cylindrical downwardly-projecting portion, as shown in Figs. 4 and 5, and the arm at this portion is provided with a circular opening extending completely through the arm. This opening is not, however, of the same diameter throughout, but is of three separate diameters, whereby two shoulders are formed in the wall of the opening, as is clearly shown in Fig. 4. Supported in this opening are two disks 17 and 18. Each disk is provided with a flange 19, projecting from its peripheral surface, which serves as a means for supporting the disks in position. Each flange is received beneath one of the shoulders above referred to and is supported by an externally-threaded ring 20, engaging screw-threads cut in the walls of the opening below the shoulders. A race-

- way is cut in the lower surface of each flange for receiving a series of balls to form a ball-bearing between the flange and the ring. The ring surrounds the disk, as shown, and acts as a guide to keep it in position. To the lower disk 17 a casing 21 is secured by means of the screws 22. This casing constitutes a support for a guide and rack for actuating the knife-carriers, as will be hereinafter described.
- Passing through the center of the disk 18 is a hollow rod 23, in which the disk is secured by a key 24. A shoulder on the rod engages the under surface of the disk and is forced into engagement therewith by a hollow internally-threaded cap 25, bearing against the upper surface of the disk and engaging a screw-thread cut on the top of the rod.
- The plate 5 of the carriage is provided with a chamber, as shown in Figs. 3 and 4, into which the cap 25 extends and in which it is free to move as the arm 12 is swung about its pivot. A block 26 is secured to the lower end of the rod 23 between a shoulder formed on the rod and a nut 27, engaging a screw-thread at the end of the rod. From this block the traveling knife-carriers are supported, as will be hereinafter described. It will thus be evident that as the disk 17 is revolved it will carry with it the casing 21 with its rack and guide, and as the disk 18 is revolved it will carry with it the rod 23 and block 26, from which the knife-carriers are supported. In order to cause the disks 17 and 18 to revolve in unison, I connect them by suitable mechanism, as by a shaft 28, journaled in the arm 12 and provided with pinions 29 and 30, engaging, respectively, with gear-teeth cut on the periphery of the disks 17 and 18, as is shown in Fig. 3.
- 31 designates a driving-shaft journaled in the casing 3 and extending longitudinally thereof. The shaft is slotted and passes through the sleeve of a bevel-gear 32, journaled in a block 33, secured to the plate 5 of the reciprocating carriage. A key 34, secured to the sleeve, engages the slot in the shaft, whereby the bevel-gear has a sliding engagement with the shaft, but is compelled to turn therewith. The sleeve is prevented from endwise movement in the block 33 by the shoulder formed by the rear side of the gear 32 and by a plate 35, secured to the end of the sleeve. The gear 32 meshes with a similar gear 36 at the upper end of a vertical shaft 37, journaled in the block 10, the axis of the shaft coinciding with the axis of the block. A gear 38 at the lower end of the shaft 37 meshes with a gear 39, supported on the lower side of the arm 12, as will be described, and this gear meshes with a gear 40 at the upper end of a tubular shaft 41. The shaft 41 is journaled on the hollow rod 23 and is free to revolve thereon. At its lower end the shaft is provided with a gear 42, which engages pinions on short vertical shafts from which the reciprocating knives are actuated, as will be hereinafter described.
- The shaft is supported in position by the engagement of the lower surface of the gear 40 with the upper surface of the disk 17 and by the engagement of the lower end of the shaft and hub of the gear 42 with the upper surface of the block 26. As will be seen in Figs. 3 and 4, the shaft 41 passes down through a central opening in the disk 17 and revolves independently thereof.
- The support for the gear 39 consists of a flanged bushing 43, screwed on the lower end of a stud 44. This bushing is prevented from turning on the stud by a pin 45, projecting downwardly therefrom and engaging a notch in the cylindrical portion of the arm 12. A plate 46, pinned to the upper face of the gear 39 and closely surrounding the stud, co-operates with the bushing in holding the gear in position.
- The block 26 is formed with a flat upper surface, and projecting upwardly from such surface is a stud 47, adapted to form a pivotal bearing for two rotary arms 48. These arms constitute rotary supports for the knife-carrying arms or frames, and, as shown in Figs. 3 and 4, consist of hub portions embracing the stud 47 and outwardly-extending portions which extend beyond the periphery of the gear-wheel 42. The hub portions of these arms are reduced to one-half the thickness of the outwardly-extending portions and are held upon the stud 47 by means of the plate 49, screwed upon a projecting portion of the stud and locked in position by screws 50, passing through the plate 49 and entering screw-threaded holes in the top of the stud.
- Pivots mounted at the outer end of each of the arms 48, so as to be capable of a lateral swinging movement, is an arm or frame 51, from which the knife-carrier is supported. The pivotal connection between the frame 51 and the arm 48 is clearly shown in Fig. 8, in which 52 represents a hollow stud seated in a projection 53 of the frame 51 and securely held therein by a set-screw 54. The stud extends above the upper surface of the arm 48 and is provided with a flange 54*, the arm 48 being held on the stud between this flange and a flange 55 at the top of the projection 53. The stud 52 has a screw-threaded engagement with the projection 53, as shown, whereby the stud may be adjusted to take up any wear between the arm and the flanges. Journaled in the stud is a short vertical shaft 56, having secured thereto a pinion 57, which meshes with the gear 42, hereinbefore referred to. At the lower end of the shaft 56 is secured a bevel-gear 58, meshing with a bevel-gear 59 on a shaft 60, journaled in a projection 61 of the frame 51. This shaft is provided with a crank 62 and crank-pin 63 for actuating the reciprocating knife. Beneath the crank-pin 63 is a projection 64 of the frame 51, and this projection is extended downwardly in the form of a cylindrical stud 65, which constitutes a pivotal bearing for the knife-carrier. Sur-

rounding the stud 65 and free to rotate and move up and down thereon is a sleeve 66. Reciprocating movements are given to this sleeve from the crank-pin 63 by means of links 5 67, through the upper ends of which the pin passes and through the lower ends of which extend trunnions projecting from a ring 68, loosely surrounding the upper end of the sleeve. The sleeve is supported in the ring 10 by means of a shoulder at the top of the sleeve and a short sleeve 69, the lower end of which rests upon an arm 70, screwed upon the lower end of the sleeve 66 and locked in position by a locking-nut 71.

15 71^a is a curved guard-plate forming a part of frame 51 and partially inclosing the connections between the crank-pin 63 and the sleeve 66.

A swiveling knife-blade 72 is mounted in 20 the outer end of the arm 70, the mounting consisting of a screw-threaded hollow block 73, engaging a screw-threaded hole in the arm. The upper end of the knife is provided with a screw-threaded portion extending 25 above the block, and the knife is supported in the block by means of a shoulder on the knife engaging an internal shoulder of the block and by nuts 74 on the screw-threaded portion above the block. The knife is held 30 from vertical movement with relation to the block, but is free to rotate on its axis. The end of the arm 70 is split to form a clamp to securely hold the block 73 in position, a screw 75 being provided for tightening this clamp.

35 The stud 65 is hollow, and free to move up and down and rotate therein is a cylindrical block 76, carried by a block 77, forming a laterally-extending arm parallel with the arm 70. Loosely journaled in the outer end of 40 the block 77 is a knife-guide consisting of a slotted cylindrical block 78, provided at its lower end with a grooved guiding-block 79 for engaging the pattern. The knife 72 passes loosely through the block, and one side 45 of the knife is engaged by a spring-pressed pin 80, mounted in a block 81, through which the block 78 passes. The spring-pin passes through an opening in the block 78 to engage the knife and the block 81 passes through an 50 elongated slot in the end of the block 77. By this construction it will be seen that the block 78 is held in the block 77 by the pin 80 and that it is capable of a limited rotary movement about its axis. A pin 82, projecting 55 from the pin 80 through a slot in the block 81, allows for the retraction of the pin 80 and the removal of the block 78. The main object of the pin 80 is, however, to form a yielding stop for the knife, whereby the knife is allowed 60 to move relatively to the carrier while in engagement with the work to avoid the dragging of the knife in the work during the continuous movement of the carrier.

The sleeve 66 and arms 70 and 77 constitute 65 a carrier for the knife 72, free to swing laterally about the axis of the stud 65 as a center. As a means for swinging the carrier

about this axis to hold the knife-guide in contact with the pattern I arrange a coiled spring 83 within the hollow stud 65, one end 70 of which is secured to the cylindrical block 76 and the other end of which is secured to a block 84, supported in the upper end of the hollow stud 65 and having ribs engaging slots cut in the inner wall of the stud, where- 75 by it is held from rotation, but is free to move up and down. The downward movement of the block 84 is limited by the ends of the slots, as will be evident from an inspection of Fig. 9.

The block 76 is free to move up and down in the stud 65, and to support it in position I provide a rod 85, having a swiveling mounting in the block 84, to the lower end of which rod the block 76 is secured. A sleeve 86, surrounding the rod 85 between the blocks 76 and 84, causes the blocks to move together, thereby preventing a compression of the spring 83 when the block 76 rises. This sleeve is shown in Fig. 9, but is omitted from Fig. 8 for the sake of clearness.

The pattern-plate, with which the guiding-block 79 engages, is carried by a spring-pressed presser-foot or clamping member, as will be described, and this presser-foot, and consequently the pattern-plate, is raised from its normal lowest position when the work is clamped by the raising of the platen. At the same time, owing to the engagement of the pattern-plate with the guiding-block 79, the arm 100 77 will be raised, the blocks 76 and 84 sliding in the stud 65. As a means for locking the knife-carrier in retracted position when swung backward against the tension of the spring 83 and at the same time to return the 105 arm 77 to the position in which the guiding-block 79 will engage the edge of the pattern when in its lowest position I provide the device shown in detail in Fig. 10. To the side of the arm 77 is pivoted a lever 87, one end 110 of which rests on a coiled spring 88 and the other end of which is adapted to engage a lug 89 on a sleeve 90, screwed on the lower end of the stud 65. The end of the lever which engages the lug 89 is provided with a projecting nose 91 at its lower side, adapted to be engaged by the lug 89 to force the lever and the block 77, upon which it is mounted, down to its normal lowest position. In operation the carrier is swung back until the 120 end of the nose 91 passes beneath the lug 89, when it is released, and as the carrier swings forward under the force of the spring the lug, acting on the upper side of the nose, depresses the lever and block 77, the carrier being finally locked in retracted position by the engagement of the vertical end portion of the lever with the lug.

The mechanism by which the knife-carriers are caused to travel about the pattern will 130 now be described.

Secured to the shaft 56 above the pinion 57 is a worm 92, meshing with a worm-gear on a shaft 93, journaled in an arm 94, projecting

upwardly and inwardly from the frame 51. The journal for this shaft is conveniently made as a separate plate, secured to the upper side of the arm 94. A bevel-gear 95 on this shaft meshes with a bevel-gear 96, mounted to rotate on a vertical stud 97, extending upwardly from the arm 94. The stud is secured to the arm by means of an externally and internally threaded nut 98, the internal thread of which engages a thread on the reduced lower end of the stud and the external thread of which engages a screw-threaded hole in the lower side of the arm. A pinion 99 is made integral with the bevel-gear 96, and a roller 100 is journaled on the stud above the pinion. The pinion 99 engages a stationary rack of a shape approximating that of the article to be cut out, and the roller 100 engages a cam-groove of similar shape to hold the pinion in engagement with the rack, as will be described. As a convenient means for securely holding the pinion 57 on the shaft 56 I provide the shaft with a flange integral therewith or rigidly secured thereto and secure the pinion to the flange by means of screw-bolts 101. The worm 92 is secured to the shaft 56 by means of a nut 102, which presses the lower face of the worm against the upper face of the pinion 57, the lower face of the worm being slotted to receive the heads of the screw-bolts 101. The rack and cam with which the pinion 99 and roller 100 engage are carried by the casing 21 and are so constructed as to be capable of adjustment to change their shape to correspond to the shape of the article to be cut out. Referring to Figs. 3, 4, and 5, it will be seen that the rack is formed on three blocks 103, 104, and 105, mounted to slide in guideways in the casing 21. The blocks 103 and 104 are, however, secured together by means of the pin 106 (see Fig. 3) and latch 107, (see Fig. 5,) so that in effect they constitute a single block. The block 103 is provided with a slot extending about three-quarters the length of the block through which the tubular shaft 41 passes. A semi-circular groove is cut in the lower face of each end block 104 and 105, and two parallel grooves are cut in the lower face of the block 103, the ends of which register with the ends of the groove in the block 104. Flanges extend downwardly from the lower surface of the blocks, the inner walls of which form a continuation of the outer walls of the grooves. Upon these flanges internal rack-teeth are cut. The racks at the edges of the block 103 are extended on bars 108, projecting from the end of the block 103 and passing through slots cut in the upper edges of the block 105, as will be clear from an inspection of Fig. 5. The lower surface of this bar is about half the width of the rack-teeth above the lower surface of the flanges on the block 103. By this construction it will be seen that the block 103, with the bars 108 and block 104 attached thereto, is free to move in the guideways of

the casing 21 independently of the block 105 and that the block 105 is also free to move.

In order to move the blocks 103 and 105 to or from each other simultaneously, I provide a pinion 109 at the lower end of a vertical shaft 110, journaled in the casing 21, which pinion engages two rack-bars 111 and 112, secured to the blocks 105 and 103, respectively. A hand-wheel 113, secured to the shaft 110, serves as a means for actuating the shaft, and a spring-pressed pin 114, engaging notches in the rim of the wheel, locks the shaft from rotation. The pin is supported in a casing secured to the lower side of the casing 21 and is provided with a flanged head 115, by means of which it may be retracted. The notches in the wheel 113 are so spaced that the teeth of the racks on the block 105 and bars 108 will register when the pin 114 is in engagement with a notch.

The racks on the blocks 103, 104, and 105 and bars 108 form a continuous rack, and the grooves in the blocks form a continuous cam-groove, except for the space between the blocks 103 and 105. To preserve the continuity of the grooves between these parts, I provide the bars 116, secured to the block 105 and having a dovetail engagement with grooves cut in the lower surface of the block 103. These bars form the inner wall of the groove, and the outer wall is formed by the bars 108.

117 designates the pattern-plate, which is secured to a presser-foot 118 in any suitable manner, as by the means shown in my patent above referred to. The presser-foot 118, to which the plate 117 is secured, is carried at the lower end of a rod 119, extending upwardly through the hollow rod 23 and supported therein by the projecting flange 120, resting on the upper end of the rod 23. Bearing against the upper end of the rod is a coiled spring 121, seated in the cap 25.

The frame of the presser-foot has two upwardly-extending projections 122 123, which enter guiding-slots cut in the block 26, the upper end of the projection 122 being notched at its inner side. The side of the block 26 is also provided with a notch leading into the guiding-slot for the projection 122. By means of this construction the presser-foot can be removed from the machine by lowering it until the upper end of the projection 122 is on a level with the notch 124 and by then moving it to the right, as viewed in Fig. 3, and then laterally at right angles, the notched upper end of the projection 122 passing through the notch 124.

125 designates the platen, between which and the presser-foot the work is clamped during the action of the cutting mechanism. The platen is provided with a suitable cutting-surface, shown as formed by a block 126, preferably of wood, securely held on the platen by the screw-bolts 127. At each side of the base of the machine is a vertical rod 128, the lower

end of which is journaled in a lug 129 and the upper end of which is journaled in an opening in the horizontal portion of a standard 2.

The platen is supported at the upper ends 5 of these rods. Connecting the two rods is a bar 130, the ends of the bar surrounding the rods and being clamped thereto by the clamping-nuts 131. The rods are actuated to raise the platen to clamp the work by means of two 10 toggle-levers of substantially the construction shown in my Patent No. 589,409, the upper arms of the levers engaging the bar 130 close to the rods. A treadle 132 actuates both toggle-levers simultaneously. To relieve 15 the toggle-levers of the greater portion of the weight of the platen, I provide coiled springs 133, surrounding the rods 128 and seated between the lugs 129 and collars 134, adjustably secured to the rods. The platen is thus supported 20 by the springs, and comparatively little power is required to raise it to a position to clamp the work. As in my Patent No. 589,409 and application Serial No. 23,599, the movement of the toggle-levers in raising the 25 platen actuates the clutching mechanism for starting the machine into operation. A shaft 135, journaled in the base 1, is provided with downwardly-extending arms 136, adapted to be struck by the toggle-lever as it reaches or 30 passes slightly beyond its straightened position. An arm at the end of the shaft 135, at right angles to the arms 136, engages a rod 137, connecting with the end of the clutch-lever 138. As the shaft 135 is rocked by the engagement 35 of the toggle-levers with the arms 136 the rod 137 will be pulled down and the clutch-lever 138 actuated to connect the loose pulley 139 to the driving-shaft 140. A spring 141 actuates the clutch-lever in the opposite 40 direction when the platen is lowered and the toggle-levers are out of contact with the arms 136. A friction-brake 142, carried by the clutch-lever, engages the loose pulley 139 when the lever is actuated to disconnect the 45 loose pulley and stop the machine. The driving-shaft 140 is journaled in a bracket depending from one of the standards 2 and is provided with the loose pulley 139 and the fast pulley 143. The shaft 140 is connected to the 50 shaft 31 by a belt passing over the loose pulley 139 and over a pulley 144 on the shaft 31.

As has been described, the support for the cutting mechanism is freely rotatable in the arm 12. It is desirable to lock the support 55 from rotation during the operation of the cutting-mechanism, and to accomplish this result I provide the disk 18 with a brake-shoe 145, set in a recess in the upper side of the disk and pressed upon by a leaf-spring inter- 60 posed between the shoe and the rear wall of the recess. A pin 146, mounted to move radially in the disk 18, bears at one end against the spring and at the other end engages a recess 147 in the rod 119, to the lower end of 65 which the presser-foot is attached. By this construction as the rod 119 rises while the work is being clamped between the platen

and the presser-foot the pin 146 will be moved outward and through the spring force the brake-shoe 145 against the wall of the 70 opening in the arm 12.

As a means for locking the arm 12 from movement on the reciprocating carriage I provide locking cam-levers 148, (see Fig. 5,) pivoted on the guide-rail 13 and adapted to 75 engage the end of the arm 12. The reciprocating carriage can also be locked in any desired position in the casing 3 by means of the clamp shown in Fig. 2. This clamp consists of a bent arm 149, loosely mounted at the 80 top of a screw-bolt 150, carried by the plate 5 of the carriage. One end of the arm overhangs the flange 4 of the casing 3 and the other end is adapted to engage the upper surface of the plate 5. By turning the screw-bolt 85 the arm is brought into engagement with the flange and plate, thus securely clamping the carriage in position.

The stock from which boot and shoe soles are cut varies considerably in thickness, and 90 it is therefore necessary to grade the soles according to this difference in thickness. Heretofore, so far as I am aware, this grading has been performed as a separate operation, either by sorting the sheets of stock before the cutting operation or by sorting the soles after being cut. In order to enable the operator to grade the soles as they are cut, and thus save the time and expense of a separate operation, I provide the machine here- 95 inbefore described with a gage for indicating the thickness of the stock being operated upon. As shown in Fig. 2, this gage consists of a pointer 151, one end of which is pivoted to the block 26 and the other end of which 100 is adapted to move over a suitable scale 152. A set-screw 153, projecting from the presser- 105 foot 118, engages a pin 154 at the side of the pointer to move the pointer over the scale 152 as the presser-foot rises during the clamping of the work. As the platen always rises to the same point, the distance through which the presser-foot moves, and consequently the extent of movement of the pointer, will be determined by the thickness of the stock. The 110 operator is thus enabled to grade the soles without loss of time as he removes them from the machine.

The attachment for trimming the surface of the platen is shown in Fig. 1, and consists 115 of a rotary cutter 155, carried at the outer end of an arm 156, pivotally mounted on the lower end of a shaft 157, journaled in a frame 158, secured to the plate 5 of the reciprocating carriage. A pinion 159 at the upper end of the 120 shaft engages the gear 38, and a belt 160, passing over pulleys on the shaft 157 and shaft of the cutter 155, serves to transmit the 125 rotary movement of the shaft 157 to the cutter. In trimming the platen the carriage is 130 locked in position on the casing 3 and the arm 156 is swung to carry the rotary cutter across the platen. The carriage is then moved forward and clamped and the cutter again

swung across the platen, the operation being repeated until the entire surface has been trimmed.

The operation of the machine above described is as follows: To position the pattern-plate 117 over any desired part of the platen, the carriage may be moved on the guiding-flanges 4 of the casing 3, the arm 12 swung laterally on the block 10 as a pivot, and the disks 17 and 18 rotated in the arm 12. The axis of the pivot for the arm 12 is concentric with the axis of the gear 38, whereby the gear 39 will always be in mesh with the gear 38 as the arm is swung on its pivot. The axis of the gear 42 is concentric with the axis of the pivot for the arms 48, by which construction the pinions 57 at the outer ends of the arms roll on the gear 42 and remain in mesh therewith as the arms and their supporting-block 27 are rotated with the disk 18. The pattern-plate having been moved to the desired position, the platen is raised and the machine thrown into operation by the mechanism hereinbefore described. Motion is transmitted from the shaft 31 to the gear 42 through the bevel-gears 32 and 36, shaft 37, gears 38, 39, and 40, and tubular shaft 41. The gear 42, meshing with the pinions 57, imparts a rapid movement of rotation to the shafts 56, and from these shafts the knives 72 are reciprocated through bevel-gears 58 59, shaft 60, cranks 62, crank-pins 63, and links 67. The knife-carriers are caused to travel about the pattern in a path corresponding approximately thereto by means of the rack and cam carried by the casing 21. A relatively slow movement of rotation is given to the pinion 99 from the shaft 56 through the worm 92, worm-gear 92^a, shaft 93, and bevel-gears 95 96. The cam and rack with which the rolls 100 and pinions 99 engage are stationary, and as the pinions revolve they will travel along the rack, thereby rotating the arms 48 about their pivots and at the same time moving the frames about their pivotal connections with the arm 48. The axes of the rolls 100 and pinions 99 coincide with the axis of the pivot for the knife-carrier, and as the rolls and pinions travel along the cam and rack the carriers will be caused to travel in a similar path. Each knife-carrier as a whole thus travels in a path of a shape corresponding to that of the cam and rack, and as it thus moves the cutting-knife is caused to travel in a path corresponding in shape to that of the article to be cut out by the engagement of the guiding-block 79 with the edge of the pattern-plate, against which it is pressed by the action of the spring 83. The swivel mounting of the knife in its carrier enables the guiding-block 79 to turn the knife on its axis to keep its edge parallel with the edge of the pattern.

In Figs. 11 to 14 I have shown a modified form of knife-carrier, which presents certain advantages over the form previously described. Referring to these figures, 161 designates a sleeve surrounding the sleeve 66

and provided with a slot through which the arm 70 extends. The upper end of this sleeve is journaled in an opening in the portion 71^a 70 of the frame 51, and the lower end, which is provided with an inwardly-projecting flange, rests on a plate 162, screwed to the lower end of the stud 65. A cap 163, securely held at the lower end of the stud 65 between the hub 75 of the plate 162 and a shoulder on the stud, serves as a bearing for the sleeve. The lower end of the sleeve 66 is received within the cap, which thus serves as a means for guiding the sleeve 66 in its reciprocating movements. For lubricating the inner surface of the sleeve 66 an oil-passage is provided in the upper end of the stud 65, as shown in Fig. 12. Surrounding the lower end of the sleeve 161 is the coiled spring 164, one end 80 of which is secured to the plate 162 and the other end of which is secured to the sleeve. The block 76 and arm 77 are free to move up and down, the block 76 being guided by the cylindrical socket in the stud 65 and the arm 90 77 being guided by the friction-roll 165, journaled in a bracket 166, secured to the sleeve 161, and by a plate 167, pivoted to the bracket 166. The spring 164 tends to rotate the sleeve 161 and, through the engagement of the slot 95 in the sleeve with the arm 70 and the engagement of the roll 165 and plate 167 with the arm 77, to swing the knife-carrier about the axis of the stud 65. A lug on the lower end of the plate 167 engaging a lug on the side of 100 the arm 77 limits the downward movement of the block 76 and arm 77. By swinging the plate 167 about its pivot the lugs may be disengaged and the block 76 and arm 77 removed. For rotating the sleeve 161 against 105 the tension of the spring 164 to swing the knife-guide away from the pattern I provide a lever 168, pivoted on the frame 51, carrying a spring-pressed pawl 169, adapted to engage a toothed wheel 170, secured to or 110 formed integral with the sleeve 161. A locking-pawl 171, mounted on the handle of the lever and adapted to engage notches in the frame 51, serves to lock the knife-carrier in retracted position. It will be seen that this 115 knife-carrier is of somewhat simpler construction than the one previously described, the spring for holding the knife-guide against the pattern is arranged to act to better advantage, and the knife-guide is free to fall by 120 gravity to its lowest position when removed from the pattern.

By means of the lever 168 the knife-carrier can be swung on its axis to remove the knife-guide from contact with the pattern 125 without taking hold of the knife-carrier itself. In this connection it is to be noted that the means for retracting the knife-carrier might be used in connection with forms of knife-carriers other than that shown in Figs. 11 to 130 14 and that mechanism other than the specific form shown might be employed without any material departure from the spirit of this feature of my invention. In practice it is found

that the construction shown in Figs. 11 to 14 allows the block 76 and arm 77 to fall freely by gravity to bring the knife-guide to its lowest position. It will be evident, however, that 5 mechanism similar to that shown in Fig. 10 for positively returning the guide to its lowest position might be provided, if desired.

Certain features of the cutting mechanism disclosed in this application and not claimed 10 herein are disclosed and claimed in my pending application, Serial No. 23,599, of even date herewith.

Having thus described the construction and mode of operation of my invention, I 15 claim as new and desire to secure by Letters Patent of the United States—

1. A machine for cutting sheet material, having, in combination, a traveling knife, means for guiding the knife in a path corresponding to the outline of the article to be cut out, a support for the knife and its guiding means and a work-support, said supports being freely movable bodily relatively to each other to position the knife and its guiding 25 means over the work, substantially as described.

2. A machine for cutting sheet material, having, in combination, a traveling knife, means for guiding the knife in a path corresponding to the outline of the article to be cut out, a support for the knife and its guiding means, and a work-support, said supports being freely movable relatively to each other in two directions to position the knife and its 35 guiding means over the work, substantially as described.

3. A machine for cutting sheet material, having, in combination, a work-support, a traveling knife, means for guiding the knife in a path corresponding to the outline of the article to be cut out, and a support for the knife and its guiding means freely movable bodily with relation to the work-support to position the knife and its guiding means over 45 the work, and means for actuating the knife, substantially as described.

4. A machine for cutting sheet material, having, in combination, a work-support, a traveling reciprocating knife, means for guiding the knife in a path corresponding to the outline of the article to be cut out, a support for the knife and its guiding means freely movable bodily with relation to the work-support to position the knife and its guiding 55 means over the work, and mechanism for actuating the knife, substantially as described.

5. A machine for cutting sheet material, having, in combination, a work-support, a traveling knife, means for guiding the knife in a path corresponding to the outline of the article to be cut out, a rotary support for the knife and its guiding means freely movable bodily with relation to the work-support to position the knife and its guiding means over 65 the work, and means for actuating the knife, substantially as described.

6. A machine for cutting sheet material,

having, in combination, a work-support, a traveling reciprocating knife, means for guiding the knife in a path corresponding to the outline of the article to be cut out, a rotary support for the knife and its guiding means freely movable bodily with relation to the work-support to position the knife and its guiding means over the work, and mechanism for actuating the knife, substantially as described. 70

7. A machine for cutting sheet material, having, in combination, a work-support, a traveling knife, means for guiding the knife in a path corresponding to the outline of the article to be cut out, a support for the knife and its guiding means, freely movable with relation to the work-support in two directions to position the knife and its guiding means over the work, and means for actuating the knife, substantially as described. 80

8. A machine for cutting sheet material, having, in combination, a work-support, a traveling reciprocating knife, means for guiding the knife in a path corresponding to the outline of the article to be cut out, a support for the knife and its guiding means freely movable bodily with relation to the work-support to position the knife and its guiding means over the work, and mechanism for actuating the knife, substantially as described. 90

9. A machine for cutting sheet material, having, in combination, a work-support, a reciprocating carriage freely movable over said work-support, an arm pivoted to said carriage, a traveling knife and means for guiding the knife in a path corresponding to the outline of the article to be cut out supported on said arm, and mechanism for actuating the knife, substantially as described. 100

10. A machine for cutting sheet material, having, in combination, a work-support, a reciprocating carriage freely movable over said support, an arm pivoted to said carriage, a traveling reciprocating knife and means for guiding the knife in a path corresponding to the outline of the article to be cut out supported on said arm, and mechanism for actuating the knife, substantially as described. 110

11. A machine for cutting sheet material, having, in combination, a work-support, a reciprocating carriage freely movable over said work-support, an arm pivoted to said carriage, a traveling knife and means for guiding the knife in a path corresponding to the outline of the article to be cut out revolvably mounted in said arm, and mechanism for actuating the knife, substantially as described. 120

12. A machine for cutting sheet material, having, in combination, a work-support, a reciprocating carriage freely movable over said work-support, an arm pivoted to said carriage, a traveling reciprocating knife and means for guiding the knife in a path corresponding to the outline of the article to be cut out, revolvably mounted in said arm, and mechanism for actuating the knife, substantially as described. 130

13. A machine for cutting sheet material, having, in combination, a knife-carrier, a stationary cam and rack comprising sections adjustable to change the shape of the cam and 5 rack, and connected mechanism for actuating the knife-carrier comprising a roll and pinion engaging the cam and rack respectively and means for rotating the pinion, substantially as described.
14. A machine for cutting sheet material, having, in combination, a knife-carrier, a stationary rack comprising sections adjustable to change the shape of the rack, and connected mechanism for actuating the knife-carrier 15 comprising a pinion engaging the rack and means for rotating the pinion, substantially as described.
15. A machine for cutting sheet material, having, in combination, a knife-carrier, a 20 block provided with parallel rack-sections, blocks provided with curved rack-sections registering with the parallel sections to form a closed rack, said blocks being adjustable to change the shape of the rack, and connected 25 mechanism for actuating the knife-carrier comprising a pinion engaging the rack and means for rotating the pinion, substantially as described.
16. A machine for cutting sheet material, having, in combination, a knife-carrier, a 30 closed rack comprising side and end sections adjustable to change the shape of the rack, and connected mechanism for actuating the knife-carrier comprising a pinion engaging the rack 35 and means for rotating the pinion, substantially as described.
17. A machine for cutting sheet material, having, in combination, a work-support, a clamping member, a support therefor, movable with relation to the work-support to position the clamping member over the work and means for locking said support from movement, substantially as described.
18. A machine for cutting sheet material, having, in combination, a work-support, a 45 clamping member, a support in which the clamping member is yieldingly mounted, movable with relation to the work-support, a device for locking said support from movement and connected mechanism for actuating the locking device by the yielding movement of the clamping member, substantially as described.
19. A machine for cutting sheet material, having, in combination, a rotating arm, a 55 frame pivoted to the arm, a knife-carrier pivoted to said frame, a shaft concentric with the pivot of the frame, a rack, a pinion mounted on said frame engaging the rack, mechanism 60 connecting the shaft and pinion and means for rotating the shaft, substantially as described.
20. A machine for cutting sheet material, having, in combination, a reciprocating carriage, a swinging arm pivoted to said carriage, a pattern-plate revolvably mounted in said arm, a reciprocating knife arranged to

travel along said pattern and mechanism for actuating the knife, substantially as described.

21. A machine for cutting sheet material, having, in combination, a reciprocating carriage, a swinging arm pivoted to said carriage, a traveling reciprocating cutter, a support therefor revolvably mounted in the arm, 75 a shaft concentric with the pivot for the arm, mechanism for actuating the same, a shaft concentric with the axis of the revolvble support, mechanism connecting said shaft and cutter and mechanism connecting said shafts, 80 substantially as described.

22. A machine for cutting sheet material, having, in combination, a reciprocating carriage, a swinging arm pivoted to said carriage, a block rotatably supported by said arm, 85 a rotating arm pivoted on said block, a frame movably mounted on said arm, a knife-carrier mounted on said frame, a reciprocating knife mounted in said carrier, and means for actuating the knife and frame, substantially 90 as described.

23. A machine for cutting sheet material, having, in combination, a vertically-movable pattern-plate, a knife-carrier movable toward and from the pattern-plate, a knife-guide for 95 engaging the edge of the pattern-plate and movable therewith, and means for returning the guide to its normal position when the knife-carrier is moved away from the pattern, substantially as described.

24. A machine for cutting sheet material, having, in combination, a vertically-movable pattern-plate, a knife-carrier comprising swinging arms, a knife mounted in one of said arms, a knife-guide for engaging the 105 edge of the pattern, mounted in the other arm, the guide and arm being movable with the pattern-plate, a locking-lever carried by the arm, a stud forming a pivotal bearing for the arm, a lug on said stud with which the 110 locking-lever engages to lock the knife-carrier and to return the arm and guide to their normal position, substantially as described.

25. A machine for cutting sheet material, having, in combination, a rotating arm, a 115 frame, pivoted to the arm, a knife-carrier pivoted to said frame, a reciprocating knife mounted in said carrier, a shaft concentric with the pivot of the frame, a rack, a pinion mounted on said frame engaging the rack, 120 mechanism connecting the pinion and the knife with the shaft, and means for rotating the shaft, substantially as described.

26. A machine for cutting sheet material, having, in combination, a platen provided 125 with a cutting-surface, a knife cutting against said surface, a device for trimming said surface, and mechanism for actuating the trimming device, substantially as described.

27. A machine for cutting sheet material, having, in combination, a knife-carrier comprising swinging arms, a knife mounted therein, a spring acting to swing the arms in

one direction and a lever and intermediate connections for swinging the arms against the tension of the spring, substantially as described.

- 5 28. A machine for cutting sheet material, having, in combination, a sleeve mounted to reciprocate upon a stud, an arm projecting from said sleeve, a block mounted in the stud, an arm projecting therefrom, a knife mounted in said arms, a slotted sleeve surrounding said first-mentioned sleeve, and a spring acting to rotate said sleeve, substantially as described.
- 10 29. A machine for cutting sheet material,

having, in combination, swinging arms, a 15 knife, mounted therein, a sleeve surrounding the pivot of said arms, a spring acting on said sleeve to swing the arms in one direction and a lever and connections for actuating the sleeves to swing the arms in the opposite direction, substantially as described. 20

In testimony whereof I affix my signature in presence of two witnesses.

JAMES J. BREACH.
